CRANKCASE SCAVENGER

Clark C. Randall, Oak Park, Ill.

Application September 19, 1945, Serial No. 617,201

3 Claims. (Cl. 123—171)

1

This invention is directed to new and useful improvements in crank case scavenger.

It is a well known fact that a serious problem is ever present due to the incomplete and unsuccessful elimination from internal combustion automotive engines of vapors, gases, and moisture produced during the operation of such engines.

Water, gum, resinous and acid-laden vapors resulting from combustion enter the crank case space as a result of leakage between the pistons and cylinder walls the volume of leakage being large or small depending upon the condition of the engine. The result is a serious deteriorating effect on lubricating oils and the production of harmful deposits and sludge that follows, all of which interferes with the efficient operation of the engine and shortens the life of the parts thereof.

It is recognized that attempts have heretofore been made to solve this problem by providing various means to ventilate the engine and crank case to remove these harmful gases and vapors but none of these means has proved efficacious for various reasons.

The usual internal combustion automotive engine is provided with ventilating or breathing means whereby fresh air is admitted into the crank case and permitted to be exhausted therefrom. Often this is induced by motion of the vehicle that tends to withdraw the air from the crank case. This airflow has also been caused by positive pressure means such as the exhaust, manifold vacuum or engine fan but in all such cases the pressure has been inadequate to thoroughly scavenge the fumes and gases and the means for accomplishing the results have been either too cumbersome or have involved change in engine design or both and some of the means used have been harmful to engine operation.

It is the primary object of this invention to provide a means for effectively removing or scavenging such undesirable gases from the crank case of an internal combustion engine that is simple in construction and that may be installed on the conventional types of automotive engines without major interference with the engine design.

Another object of this invention is to provide a crank case scavenger whereby an adequate air pressure is created and so directed to thoroughly scavenge the crank case at all times during engine operations.

Still a further object is to provide such a device whereby the conventional automotive engine

2

is utilized to produce the air pressure necessary to accomplish the desired results.

And still another object of this invention is to provide an improved crank case scavenger that will be safe in operation, will not interfere in any way with the normal operation of the engine and may be quickly fitted to and become part of any conventional automobile or truck engine.

A further object is to provide a unitary structure comprising air scoop and aspirating means of simple design that may readily be attached to a conventional automotive engine to operate so as to thoroughly scavenge the engine.

The word "scavenger" has been used herein advisedly as distinguished from "ventilator." This distinction is that a "ventilator" does not cause pressure that will adequately remove the fumes while a "scavenger" creates adequate pressure to in fact remove the undesirable gases as well as ventilate the engine.

In the drawings:

Fig. 1 is a side elevation view of a conventional internal combustion engine for automobiles or trucks utilizing one form of the invention herein described.

Fig. 2 is a side elevation view of portion of another conventional form of such an engine on which is installed a scavenger embodying this invention.

Fig. 3 is a side elevation view of a portion of still another conventional form of engine utilizing this invention by means of a unit attachment.

Fig. 4 is a plan view of the air pressure scoop attachment used as a part of one form of the crank case scavenger herein described.

Fig. 5 is a plan view of a conventional flywheel cover cut away to receive air scoop shown in Fig. 4.

Fig. 6 is a sectional view taken along line 6—6 of Fig. 1.

Fig. 7 is a plan view of the scavenger unit comprising the flywheel air scoop and venturi as shown in Fig. 3.

Fig. 8 is a side elevation view of another form of a scavenger embodying the invention herein described.

In detail the engine block is indicated by the reference character 1, the crank case 2, and the flywheel casing 3. A typical air inlet to the crank case is shown at 4 and the breather outlet at 5.

An aspirator or Venturi attachment 6 is connected with breather outlet 5 by any well known means, such as hose and clamp connection 5a. This attachment 6 is a unit comprising an outlet extension 7 and a larger air pressure conduit 8.

surrounding outlet extension 7 and extending from a point above the lower end of conduit 7 to a point past the lower end of the outlet extension. The upper end of conduit 8 is secured to conduit 7 and closed by any well known method, as shown at 8a. Conduit 8 is provided with an air pressure receiving connection 9 extending at right angles to the conduit 8 and joining the conduit 8 at a point above the downwardly extending end of outlet extension 7. The lower end of conduit 8 is sheared as shown to provide an angular outlet orifice 10.

Thus the aspirator attachment 6 provides a Venturi unit to function as hereinafter explained.

The conventional flywheel casing 3 is provided with the usual removable cover 11 that is cut away (Fig. 5) as at 12 to provide an air outlet 13 to the air pressure scoop attachment shown in Fig. 4. The flywheel of usual construction is shown at 14 having teeth 14 for connection with a conventional starter. The flywheel casing is provided with the usual breather openings (not shown) or an air opening may be made if needed.

The air scoop attachment, Fig. 4, is formed with a connecting plate 15 curved to fit the contour of the flywheel cover 11. It is provided with holes 15a that will align with holes 15b of the cover 11 whereby it can be secured to the flywheel casing cover 11 in any well known manner. This air scoop attachment plate 15 is formed with an elliptical air outlet 16 leading to conduit 17. Thus it is seen that when the air scoop is attached to the flywheel cover the air outlet 16 will be adjacent the teeth 14 of flywheel 13. Conduit 17 extends forwardly from the flywheel and the outlet end and the connection 9 are joined together by a section of air pressure conduit 18 by any well known clamping means.

With the construction hereinabove described it can be seen that whenever the engine is in operation the flywheel will rotate in the direction of the arrow, Fig. 6, and the flywheel teeth 14 will move rapidly past outlets 12 and 16 and will act as a blower to force a substantial amount of air outwardly through conduit 17.

In operation, this positive and substantial air pressure will be exerted in the direction of the arrows through conduits 17 and 18, connection 9, downwardly past outlet extension 7 and to the atmosphere through orifice 10. This rapid movement of air past outlet extension 7 will create a suction or vacuum therein to rapidly withdraw gases from the crank case to effect the needed scavenging action. As this action progresses fresh air will be drawn into the crank case through breather inlet 4. The movement of the automobile in a direction from left to right will cause air to pass the angular outlet orifice 10 to create an added suction to assist in the withdrawal of the crank case fumes. It is to be noted that this action alone is far from sufficient to effect the needed result.

It has been found and demonstrated that the pressure created by the flywheel blower action is of such strength that substantially complete and thorough crank case scavenging is obtained.

In the modification illustrated in Fig. 2 the main features are identical with those hereinabove described and for this reason the reference characters remain the same for these common features. The only difference between the structures illustrated in Figs. 1 and 2 is the position of the breather outlet of the engine. In Fig. 1 the outlet is shown coming from the side of the engine block but in Fig. 2 it is shown as located

on the lower flange of the engine block. The breather outlet here is indicated by 19 with the usual aspirator or Venturi attachment 6 connected thereto, by connector 20.

In the modification shown in Fig. 3 the breather outlet 21 is positioned in the side of the engine block 1, near the flywheel casing 3. This permits the use of a unitary structure shown in Fig. 7 in which the air scoop and venturi are formed as a unit. Referring to Fig. 7 the air scoop is indicated generally by reference character 22 and the venturi by 23. The air scoop comprises the same attachment plate 24 having outlet air opening 25 and conduit 26 leading therefrom. This conduit 26 becomes the air pressure receiving conduit of venturi 23 connecting with outlet conduit 27 which surrounds the outlet extension 28 in the manner hereinbefore described. The inlet end 29 of conduit 28, in this modification is then connected by means of hose and clamps, or any other well known means to the outlet breather 21. This provides a unitary structure that can be easily attached to accomplish the thorough scavenging action when the engine is in operation.

In the modification shown in Fig. 8 the aspirating means is the same as shown in Fig. 1 but instead of the air pressure receiving connection 9 being joined to an air scoop receiving its pressure from the flywheel it is directly connected with the outlet 30 of a small blower 31 that is mounted to the side of the engine block by any desired bracket means. Blower 31 is operated by an associated electric motor 32 operating from the electrical circuit of the automobile or truck engine.

It is of course more desirable to utilize the flywheel for the blowing means but in some instances the separate, independent blowing means shown in Fig. 8 may be more adaptable. However, in both cases the full blowing capacity is utilized so as to produce adequate pressure to withdraw the fumes.

In some instances the flywheel casings do not have removable covers. In such installations it is apparent that the air outlet 12 and holes 15b shown as cut from the cover in Fig. 5 will be cut into the bottom of the casing.

I claim:

1. A crank case scavenger for an internal combustion engine provided with a breather system for the crank case and having a flywheel with teeth on its periphery, comprising an air scoop attachment adapted to be positioned adjacent the teeth of the flywheel for receiving the air moved by said teeth, a Venturi attachment adapted to be connected with the outlet portion of the breather system and a conduit connecting said air scoop attachment with said Venturi attachment whereby the air moved by the teeth of the flywheel will be directed past the outlet of the breather system to withdraw fumes from the crank case.

2. A crank case scavenger for an internal combustion engine provided with a breather system for the crank case and having a flywheel with teeth on its periphery and a cover therefor, comprising an air scoop attachment, a Venturi attachment, a conduit connecting the inlet of the venturi with the breather outlet, an air outlet in said flywheel cover adjacent the teeth of the flywheel, said air scoop comprising a plate formed for attachment to said cover over said air outlet, an air outlet adapted to be aligned with the cover air outlet when the plate is attached, a conduit leading from the air outlet of said plate and means connecting said conduit with said Venturi.

attachment whereby air moved by the teeth of the flywheel is directed through the venturi to effect a rapid withdrawal of air from the crank case.

3. A crank case scavenger for an internal combustion engine provided with a crank case and having a flywheel with teeth on its periphery, comprising an air scoop attachment adapted to be positioned adjacent the teeth of the flywheel

for receiving the air moved by said teeth, a Venturi attachment adapted to be connected with the interior of the crank case and a conduit connecting said air scoop attachment with said Venturi attachment whereby the air moved by the teeth of the flywheel will be directed through the venturi to withdraw fumes from the crank case.

CLARK C. RANDALL.
